DESIGN FOR A SHELF TRUCK

Wilbur Henry Adams, Erie, Pa., assignor to The Colson Corporation, Elyria, Ohio, a corporation of Ohio

Application January 24, 1944, Serial No. 112,309

Term of patent 7 years

(Cl. D14—3)

To all whom it may concern:

Be it known that I, Wilbur Henry Adams, a citizen of the United States, residing at Erie, in the county of Erie and State of Pennsylvania, have invented a new, original, and ornamental Design for a Shelf Truck, of which the following is a specification, reference being had to the accompanying drawing, forming a part thereof.

Figure 1 is a perspective view as viewed from one side of the shelf truck of my new design; and

I claim:

The ornamental design for a shelf truck, substantially as shown.

WILBUR HENRY ADAMS.
